WILLIS J. SMITH, OF OTTUMWA, IOWA

INTERNAL COMBUSTION ENGINE COOLING SYSTEM

Application filed November 20, 1931. Serial No. 576,400.

The present invention relates to a cooling system for automobile engines and other gas engines and has for its primary object to provide, in a manner as hereinafter set forth, a device of this character embodying a novel construction, combination and arrangement of parts through the medium of which damage to the radiator or to the engine block or head of the automobile or other gas engines due to the freezing of the liquid in the cooling system will be prevented.

Another important object of the invention is to provide a radiator comprising a novel construction and arrangement whereby the likelihood of the cooling liquid in said radiator being frozen is materially reduced, the construction further functioning to thaw the radiator comparatively rapidly in case the liquid therein should be frozen.

Other objects of the invention are to provide an automobile radiator which will be simple in construction, strong, durable, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in front elevation of a radiator in accordance with the present invention.

Figure 2 is a view in vertical section through the radiator.

Figure 3 is a fragmentary view on an enlarged scale in horizontal section taken substantially on the line 3—3 of Figure 1.

Referring now to the drawings in detail, it will be seen that the reference numeral 1 designates the forward portion of the frame of an automobile and 2 designates a portion of the engine. Mounted on the frame 1 in the usual manner are the front springs 3 to which the axle 4 is connected.

The invention comprises a tank 5 of suitable size, shape and preferably of metal which is mounted in any suitable manner in

the frame 1 forwardly of the engine 2. The tank 5 is enclosed in a covering 6 of heat insulating material. Adjacent one end the tank 5 is provided with a filling neck 7 which is closed by a removable closure 8. The reference numeral 9 designates a drain cock for the tank 5.

Mounted on the tank 5 is a radiator designated generally by the reference numeral 10, said radiator 10 comprising the upper and lower tanks 11 and 12, respectively. Extending between the tanks 11 and 12 are the comparatively small tubes 13 and the comparatively large diameter tubes 14. As best seen in Figure 2 of the drawings, the upper ends of the small tubes 13 are flush with the bottom of the upper tank 11 while the large tubes 14 project above the bottom of said tank 11. A pipe 15, having a check valve 16, therein, depends from the lower radiator tank 12 into the tank 5 for returning the cooling liquid to said tank 5 from the radiator. The upper tank 11 of the radiator 10 is connected to the head of the engine 2 for receiving the cooling liquid therefrom by a conduit 17. The reference numeral 18 designates a vent pipe in the upper radiator tank 11 which is primarily for the escape of steam or liquids.

The reference numeral 19 designates the fan shaft of the engine 2 which is rotatably supported in the bracket 20 which projects forwardly from said engine 2. A conventional fan 21 is fixed on the forward end portion of the shaft 19 and is located adjacent the rear of the radiator 10. A vertical pump shaft is designated by the reference numeral 22 and extends rotatably downwardly into the tank 5 through the top of said tank 5. The shaft 22 is journaled in a bearing 23 provided therefor on the forward end of the engine 2 and also in a bearing provided therefor on the forward end portion of the bracket 20. A worm gear connection 24 operatively couples the pump shaft 22 to the fan shaft 19 for actuation thereby. The fan shaft 19 is driven from the crank shaft of the engine 2 by the usual belt and pulley connection. The pump 25 may be connected to the engine in any other suitable manner or driven by any other suitable means.

The pump shaft 22 is operatively connected to a pump 25 of any suitable type which is mounted in the lower portion of the tank 5. A conduit 26 extends from the pump 25 to the block of the engine 2 for delivering the cooling liquid from the tank 5 to the block.

In use, the liquid is impelled from the tank 5 through the engine block by the pump 25, as will be apparent. From the engine 2 the liquid rises through the conduit 17 into the upper tank 11 of the radiator 10. From the upper tank 11 of the radiator the liquid normally flows through the small tubes 13 by gravity to the lower radiator tank 12 and returns to the reservoir tank 5 through the pipe 15. When the engine is not in operation the liquid which is in said engine and in the conduit 17 drains back through the conduit 26 and the pump 25 into the reservoir 5 and, of course, the cooling liquid in the radiator 10 will also drain into the reservoir 5. Thus, no liquid is left in the radiator or engine to freeze. The liquid in the reservoir 5 is protected against freezing by the insulating covering 6 and, if desired, a comparatively small quantity of anti-freeze liquid may be mixed with the usual cooling liquid. Even should the liquid in the reservoir 5 freeze no damage will result as the reservoir 5 is constructed to withstand considerable pressure and in addition sufficient room is provided to permit expansion of the liquid. The check valve 16 prevents the circulation of air and the consequent loss of heat from said reservoir 5.

As before stated, the liquid normally flows from the upper radiator tank 11 to the lower radiator tank 12 through the small tubes 13. Should the liquid in said small tubes freeze and obstruct the same so that liquid cannot pass therethrough, the liquid will accumulate and rise in the upper radiator tank 11 to the level of the top of the tubes 14 and flow downwardly through the large tubes 14. Obviously, the liquid will not freeze in the large tubes 14 as readily as it does in the small tubes 13. The presence in the large tubes 14 of unfrozen water at a higher temperature than the liquid in the small tubes 13 will assist materially in thawing the frozen liquid in adjacent small tubes 13. It will be evident that operation of the engine during such periods as there is frozen fluid in the small tubes will heat the fluid remaining in the system above normal temperature and this heated fluid passing through the large tubes 14 will quickly thaw the small tubes. Any desired number of the large tubes 14 may be provided. If desired, the radiator may be of cellular cross section or of any other type. It is the variation in cross section of the tubes which permits one to freeze while the other does not.

While the radiator is intended particularly

for use on automobiles, same obviously may be used on any other vehicles such as tractors or trucks or with any water cooled engine.

It is believed that the many advantages of an automobile radiator constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. In an internal combustion engine cooling system including an engine water jacket and a radiator, an insulated reservoir supported below the radiator, a gravity drain from the radiator to the reservoir, a pipe leading from the water jacket into the reservoir, a second pipe leading from the water jacket to the upper part of the radiator, means for circulating water kept warm in the reservoir through the first pipe, the water jacket, the second pipe and into the upper part of the radiator for travel downward therein, and a tube of relatively large cross section extending vertically through the radiator and emptying into the reservoir for receiving and conveying warm water circulated to the upper part of the radiator and being heated thereby for thawing the radiator in case of freezing thereof.

2. In an internal combustion engine cooling system including a water jacket and a radiator having small water tubes, an insulated reservoir supported at a level below the radiator, a gravity drain leading from the radiator to the reservoir, a water jacket feeding pipe leading from the reservoir to the water jacket, a radiator feed pipe leading from the water jacket to the upper part of the radiator, circulating means for circulating water kept warm in the reservoir through the water jacket feeding pipe, the water jacket, and the radiator feeding pipe into the upper part of the radiator, and a tube of relatively large cross section extending through the radiator from the upper part thereof downwardly for thawing adjacent frozen water tubes of the radiator.

3. In an internal combustion engine cooling system including a water jacket and a radiator, an insulated reservoir supported at a level below the radiator, a gravity drain leading from the radiator to the reservoir, a water jacket feeding pipe leading from the reservoir to the water jacket, a radiator feed pipe leading from the water jacket to the upper part of the radiator, circulating means for circulating water kept warm in the reservoir through the water jacket feeding pipe, the water jacket, and the radiator feeding pipe into the upper part of the radiator, and

a warm water conveying pipe extending through the radiator from the upper part thereof downwardly for thawing adjacent frozen water containing elements of the radiator, said warm water conveying pipe being of relatively large cross section whereby the water therein will not freeze readily.

4. In an internal combustion engine cooling system including a water jacket and a radiator, an insulated reservoir supported at a level below the radiator, a gravity drain leading from the radiator to the reservoir, a water jacket feeding pipe leading from the reservoir to the water jacket, a radiator feed pipe leading from the water jacket to the upper part of the radiator, circulating means for circulating water kept warm in the reservoir through the water jacket feeding pipe, the water jacket, and the radiator feeding pipe into the upper part of the radiator, and a pipe of relatively large cross section extending through the radiator from the upper part thereof downwardly for thawing adjacent frozen water containing elements of the radiator, said warm water conveying pipe being of relatively large cross section so that the water therein will not freeze readily, and check valve means in said drain for preventing escape upwardly therethrough of air and 30 heat from the reservoir.

5. A non-freezing cooling system for a water jacket equipped internal combustion engine comprising a radiator, water circulating means connecting the lower part of radiator to lower part of water jacket and the upper part of radiator to upper part of water jacket, a pump for circulating the water in radiator and water jacket, said radiator comprising a plurality of spaced rows of vertical water tubes, a header on the upper ends of the plurality of tubes and communicating therewith, the upper end of said tubes being below the normal water level in the header, other tubes having their upper ends elevated above said water level and located between the rows of tubes, said other elevated tubes being of larger cross section to delay freezing of the water therein beyond the freezing of water in the first tubes, so that upon obstruction of the first tubes by freezing of the water therein at a low temperature the water level in the header will be raised above its normal level by the continued circulation of water by the pump through the water jacket and rise to the level of the upper ends of the said other elevated tubes and the water will flow downwardly through the elevated tubes and thaw adjacent frozen and obstructed first tubes.
